UNITED STATES PATENT OFFICE.

NELSON H. STURGIS, OF GUTHRIE, OKLAHOMA.

SUSPENSION-BRIDGE.

1,143,866.

Specification of Letters Patent. Patented June 22, 1915.

Application filed October 11, 1913. Serial No. 794,702.

To all whom it may concern:

Be it known that I, NELSON H. STURGIS, a citizen of the United States, residing at Guthrie, in the county of Logan and State 5 of Oklahoma, have invented a new and useful Suspension-Bridge, of which the following is a specification.

The invention relates to improvements in suspension bridges.

10 The object of the present invention is to improve the construction of suspension bridges and to provide a simple and comparatively inexpensive construction adapted to relieve from wear, due to expansion, 15 contraction and vibration, the suspension cables, which sustain the entire weight of the bridge between the towers, and to equip the bridge with means for maintaining in proper spaced relation the hanger rods 20 which support the needle beams and floor structure whereby the camber of the bridge will be maintained the same at all times.

A further object of the invention is to enable the needle beams and floor structure 25 to be adjusted vertically to preserve a level condition of the same and to also adjustably connect the hand railing with the hanger rods to maintain the railing plumb.

Another object of the invention is to 30 firmly anchor the floor structure in place and stiffen the bridge sidewise and thereby lessen the strain on the laterals.

With these and other objects in view the invention consists in the construction and 35 novel combination of parts hereinafter fully described, illustrated in the accompanying drawings, and pointed out in the claims hereto appended; it being understood that various changes in the form, proportion, 40 size and minor details of construction, within the scope of the claims, may be resorted to without departing from the spirit or sacrificing any of the advantages of the invention.

45 In the drawings:—Figure 1 is a side elevation of a suspension bridge constructed in accordance with this invention. Fig. 2 is an enlarged side elevation of a portion of the suspension bridge. Fig. 3 is a horizontal sectional view of the suspension bridge. Fig. 4 is a transverse sectional view on the line 4—4 of Fig. 2. Fig. 5 is an enlarged horizontal sectional view through one of the needle beams. Fig. 6 is a transverse sectional view on the line 6—6 of Fig. 1. Fig.

7 is a detail vertical sectional view through the upper portion of one of the towers or columns, taken longitudinally of the bridge. Fig. 8 is a similar view taken transversely of the bridge. Fig. 9 is an enlarged detail 60 sectional view illustrating the construction of the cable clamps for connecting the hanger rods, the spacing rods and the inclined truss rods with the cable. Fig. 10 is an enlarged detail sectional view illustrating the manner of securing the lower terminals of the inclined truss rods to the 65 needle beams. Fig. 11 is a detail sectional view on the line 11—11 of Fig. 2, illustrating the means for adjustably connecting the 70 hand railing with the hanger rods. Fig. 12 is a detail sectional view on the line 12—12 of Fig. 2, illustrating the means for clamping the floor to the stringers.

In the accompanying drawings in which 75 is illustrated the preferred embodiment of the invention, 1, 1 designate a pair of suspension cables located at opposite sides of the suspension bridge and designed to sustain the entire weight of the same between 80 supporting columns or towers 2 which are mounted upon shore abutments or foundations 3 of masonry or any other desired construction. The towers or columns which preferably consist of structural steel are 85 illustrated in the drawings as consisting of spaced vertical flanged beams or members 4 connected by a lattice or lacing 5 to form a trussed structure, and also connected at the top by a cap piece 5^a secured to the side 90 beams or members 4 by angle plates 6 or other suitable means. Any other preferred construction of columns or towers may be employed, and said columns or towers are also preferably connected at their upper 95 portions by a horizontally disposed transversely arranged trussed frame 7 of structural steel or other suitable material. The columns or towers are equipped at their tops beneath the cap plates or pieces 5 with 100 grooved pulleys or sheaves 8 receiving and forming rests for the cables 1 and adapted to permit the same to yield to the expansion and contraction and vibration without causing the wear which necessarily results 105 when relatively fixed cable rests are employed. The grooved pulleys or sheaves are mounted upon shafts or spindles 9 piercing the side beams or members of the towers or columns and slidably secured to the same. 110

The shore ends 10 of the suspension cables 1 are suitably secured to anchors 11 preferably in the form of bars embedded in anchor abutments 12, as illustrated in Fig. 1 of the drawings, but the terminals of the cables may be anchored in any other preferred manner and in practice the suspension cables will be of sufficient size to sustain the weight of the bridge, and while a single cable 1 is shown at each side of the bridge in the accompanying drawings, yet it will be readily understood that a plurality of cables may be employed instead of providing a single excessively thick cable where great strength is necessary.

Suspended from the cables 1 at intervals throughout the length of the bridge are vertical hanger rods 13 provided at their upper ends with eyes 14 through which pass transverse bolts 15 which also pierce the sides 16 of substantially U-shaped clamps 17 centrally thereof. The clamps are composed of straight or flat sides 16 and an approximately cylindrical top portion 18 connecting the sides and fitting around and adapted to clamp the cable 1. The clamp is firmly secured to the cable 1 and is prevented from slipping thereon by the bolt 15 which passes through the centers of the sides 16 and by upper and lower bolts 19 and 20 arranged in pairs at the ends of the clamp and extending through eyes 21 and 22 of spacing rods 23 and oppositely inclined truss rods 24 and securing the same to the clamp. The eyes 21 of the spacing rods are located at the upper portions of the clamps at opposite sides of the hanger rods, and the upper ends of the inclined truss rods are located below the eyes of the hanger rods. By firmly securing the clamps to the cables and spacing them by the rods 23 as hereinafter fully explained, the camber of the bridge is maintained the same at all times. The bolts 15, 19 and 20 which connect the sides of the clamp are equipped with nuts and are adapted to draw the sides of the clamp together to produce the desired clamping or gripping action on the cable. The lower ends of the hanger rods 13 extend through vertically aligned openings 25 of horizontal plates 26 riveted or otherwise secured to the top and bottom flanges of transverse needle beams 27 which preferably consist of I-beams. The upper and lower horizontal terminal plates 26 which are fitted against the top and bottom flanges of the needle beams form extensions of the said flanges and provide simple, strong and effective means for connecting the lower ends of the hanger rods with the needle beams at the median plane of the same without piercing the webs of the needle beams but the lower ends of the hanger rods may pass directly through the said needle beams if desired. The lower ends of the hanger rods are threaded at 28 to receive

nuts 29 which adjustably connect the needle beams with the hanger rods and by adjusting the nuts 29 the needle beams and the floor structure supported by the same may be maintained in proper level position. The series of rods 23 which maintain the clamps in proper spaced relation extend longitudinally of the suspension cable 1 and are located beneath the same and each rod is arranged substantially parallel with a short section of the adjacent cable 1, and the series of rods following the curve of the cables are provided with turn-buckles 30 located at a point intermediate of the ends of the spacing rods and connecting threaded sections thereof and adapted to adjust the said rods and maintain the same under the proper tension. The spacing rods 23 at the ends of the span of the bridge are secured to the columns or towers between the vertical side beams or members thereof by bolts 31 arranged at points adjacent to the pulleys or sheaves 8.

The oppositely inclined truss rods 24 which are crossed at opposite sides of the bridge are provided at points intermediate of their ends with turn-buckles 32 and have lower threaded terminals 33 extending through openings 34 in the web portions of the needle beams 27 and through openings 35 and 36 in vertically disposed angle plates 37 riveted to the side faces of the webs of the needle beams opposite the openings 34, as clearly illustrated in Fig. 10 of the drawings.

The angle plates 37 consist of vertical terminal attaching portions 38 and approximately V-shaped intermediate portions composed of upper and lower sides or wings arranged at an angle to the webs of the needle beams. The lower sides or wings of the angularly disposed portions of the angle plates 37 are set perpendicularly to the inclined truss rods and they form abutments for nuts 39 which are arranged on the threaded terminals 33 of the inclined truss rods.

The needle beams are braced by laterals or diagonally disposed truss rods 40 crossed centrally between the needle beams and having threaded terminals 41 extending through openings 42 in the webs of the needle beams and equipped with nuts 43 which engage angle plates 44 disposed horizontally and constructed substantially the same as the vertically disposed angle plates, being provided with terminal attaching portions fitted against and riveted to the webs of the needle beams. The intermediate angular portions of the angle plates 44 have inner and outer openings 45 and 46, and the outer sides or wings are set perpendicularly to the diagonal truss rods which are provided with turn-buckles 47. The angle plates which are constructed of steel or other suitable material are designed to take the place of angle wash-

ers ordinarily employed at such points to provide angularly disposed abutting faces for nuts or other fastening means.

The floor structure comprises longitudinal stringers 48 and 49, the stringers 48 being arranged at the sides of the bridge and preferably consisting of channels, as shown, while the intermediate stringers 49 are preferably formed by I-beams, as clearly illustrated in Fig. 4 of the drawings. The stringers which are suitably secured to the needle beams will in practice, as indicated in Fig. 3 of the drawings, break joints with one another so that the joints of all the stringers will not occur at the same needle beam. The stringers 48 and 49 support flooring 50 consisting of transversely disposed boards laid upon the stringers 48 and 49 and firmly clamped against the same by longitudinal guard rails 51 located at opposite sides of the floor structure and connected at intervals with the side stringers 48 by substantially vertical hook bolts 52 engaging under the said side stringers 48 and piercing the flooring and the guard rails and having upper threaded ends 53 which are equipped with nuts 54. The hook bolts 52 with their nuts 54 adjustably and detachably connect the guard rails with the side stringers and enable the desired clamping action to be exerted on the flooring and at the same time they are adapted to permit the boards of the flooring to be readily removed and renewed when worn.

The bridge is equipped at opposite sides with hand railings 55 composed of vertical posts 56 and spaced upper and lower horizontal bars 57 and 58 which are connected by lacing or trussing 59. The horizontal bars are flanged as shown and the posts which are also flanged are suitably secured at their lower ends to the side stringers 48 and are supported by outer inclined braces 59^a mounted upon terminal projecting portions of angle bars 70. The hand railing is adjustably connected with the hanger rods by hook bolts 60 having their hooks engaged with the said hanger rods and provided with threaded inner terminal bolts 61 piercing the adjacent posts of the hand railing and provided with nuts 62 arranged in pairs and clamping the said posts at opposite sides thereof. By this construction the posts are adjustably connected with the hanger rods and the hand railings are thereby adapted to be maintained in a plumb condition.

The inclined truss rods at the terminals of the span of the suspension bridge are provided at the towers or columns with threaded terminals 63 piercing plates 64 and 65 and having nuts 66 which engage enlargements 67 formed on the plates 64 and having angularly disposed faces arranged perpendicularly to the inclined truss rods. The span or central portion of the bridge is of uniform width and the terminal portions

68 of the frame structure of the bridge beyond the towers are preferably widened and increase in width outwardly, as indicated in Fig. 3 of the drawings. This stiffens the bridge sidewise and is adapted to lessen the strain on the laterals or diagonal truss rods. The widened end portions 68 extend from the shore abutments to supplemental abutments 69 being supported by the said abutments and the terminal portions of the suspension cables.

What is claimed is:

1. A suspension bridge including suspension cables, means for supporting the same, hanger rods depending from the cables at short intervals and adapted to support a floor structure, and series of spacing rods connected with and maintaining the hanger rods in proper spaced relation, each spacing rod being arranged in substantial parallelism with a short section of the adjacent cable and the series of spacing rods following the curve of the cables.

2. A suspension bridge including suspension cables, clamps arranged on the suspension cables and composed of spaced sides and a top connecting portion, depending hanger rods having their upper terminals secured between the sides of the clamps centrally thereof, said hanger rods being adapted to support a floor structure, a series of spacing rods located beneath the cable and extending longitudinally thereof and having their terminals secured between the sides of the clamps at the upper portions thereof at opposite sides of the hanger rods, and oppositely inclined truss rods having their upper ends secured between the sides of the clamps below the terminals of the spacing rods.

3. A suspension bridge including suspension cables, means for supporting the same, cable clamps arranged on the cables at short intervals and provided with adjusting means for causing the clamps to grip the cables, hanger rods connected with and depending from the clamps and adapted to support a floor structure, and series of spacing members located at and extending longitudinally of the suspension cables and connected with the clamps to hold the same against movement on the cables and positively maintain the said clamps in proper spaced relation, each spacing member being arranged in substantial parallelism with a short section of the adjacent cable and the series of spacing members following the curve of the cables.

4. A suspension bridge including suspension cables, means for supporting the same, clamps arranged on the suspension cables, hanger rods depending from the clamps and adapted to support a floor structure, and series of spacing rods located adjacent to the cables and having their terminals secured within the clamps and provided with adjusting means for varying the length of the

4
rods to position the clamps along the cables, each spacing rod being arranged in substantial parallelism with a short section of the adjacent cable and the series of spacing rods following the curve of the cables.

5. A suspension bridge, including cables, means for supporting the same, hanger rods depending from the cables, needle beams connected with the lower ends of the hanger rods, stringers supported by the needle beams, hand railings arranged at opposite sides of the bridge and supported upon and connected at the bottom with the stringers, and adjustable means for connecting the
- 10 hand railings with the hanger rods for maintaining the said railings in a plumb position.
- 15 6. A suspension bridge including cables, means for supporting the same, hanger rods

depending from the cables, needle beams 20 connected with the lower ends of the hanger rods, a floor structure supported by the needle beams, hand rails arranged at opposite sides of the bridge, supported upon and connected at the bottom with the floor structure, and adjustable hook bolts arranged horizontally with their hooks engaging the hanger rods and connecting the hand railings with the same to maintain the said hand railings in a plumb position.

25 In testimony, that I claim the foregoing as my own, I have hereto affixed my signature in the presence of two witnesses.

30 NELSON H. STURGIS.
